(57) **CLAIM**

The ornamental design for a wheelchair, as shown and described.

DESCRIPTION

4.-5. Wheelchair

4.1 is a front elevation view of a wheelchair showing our new design in accordance to a first embodiment;

4.2 is a rear elevation view thereof;

4.3 is a right side elevation view thereof;

4.4 is an enlarged and partial right side elevation view thereof for portion in Box A as shown in 4.3;

4.5 is a left side elevation view thereof;

4.6 is an enlarged and partial left side elevation view thereof for portion in Box B as shown in 4.5;

4.7 is a top plan view thereof;

4.8 is a bottom plan view thereof;

4.9 is a front and right side perspective view thereof;

4.10 is a front and right side perspective view thereof for portion in Box C as shown in 4.9; and

4.11 is a rear and right side perspective view thereof.

5.1 is a front elevation view of a wheelchair showing our new design in accordance to a second embodiment;

5.2 is a rear elevation view thereof;

5.3 is a right side elevation view thereof;

5.4 is an enlarged and partial right side elevation view thereof for portion in Box D as shown in 5.3;

5.5 is a left side elevation view thereof;

5.6 is an enlarged and partial left side elevation view thereof for portion in Box E as shown in 5.5;

5.7 is a top plan view thereof;

5.8 is a bottom plan view thereof;

5.9 is a front and right side perspective view thereof;

5.10 is a front and right side perspective view thereof for portion in Box F as shown in 5.9; and

5.11 is a rear and right side perspective view thereof.
